[57] **ABSTRACT**

A multistable circuit includes a plurality of latching pairs, each preferably comprising transistors connected in a feedback circuit. Each latching pair is coupled to a transistor of the next latching pair, for presetting such transistor for conduction. The latching pairs alternately receive current from a current switching means, and when the current is switched, the latching pair having the preset transistor immediately conducts.

**MULTISTABLE CIRCUIT INCLUDING ELEMENTS
PRESET FOR CONDUCTION**

BACKGROUND OF THE INVENTION

A binary divider or flip-flop is one of the basic circuits in computers, frequency counters, and other digital equipment. The conventional binary flip-flop uses charge commutative devices such as capacitors or the stored charge of semiconductors when switching from one state to another. This type of arrangement is characterized by several disadvantages, especially for high frequency operation. Commutative energy transfer must take place during transition and therefore transition may be rather slow. The conventional circuit is also critical as to stray capacitance and transistor high frequency parameters. Moreover, the conventional circuit is usually sensitive to the input drive rise time.

SUMMARY OF THE INVENTION

According to the present invention, a multistable circuit includes a plurality of latching pairs or circuits wherein the latching pairs or circuits are adapted to operate consecutively so that only one from a number thereof is on at one time. Coupling means extend from each latching circuit to an active element of the next latching circuit for presetting the same for conduction. Current switching means transfer current between alternate latching circuits, and when switching takes place, the latching circuit including the preset element will immediately conduct. The circuit is operative at frequencies from substantially zero to 600 megahertz.

It is an object of the present invention to provide an improved multistable circuit operative over a wide frequency range.

It is another object of the present invention to provide an improved multistable or divider circuit which is substantially insensitive to input drive rise time.

It is another object of the present invention to provide an improved multistable circuit which does not employ commutative time constant means.

It is another object of the present invention to provide an improved multistable circuit which is relatively simple, and which is easily adapted to integrated circuit techniques.

The subject matter which I regard as my invention is particularly pointed out and distinctly claimed in the concluding portion of this specification. The invention, however, both as to organization and method of operation, together with further advantages and objects thereof, may best be understood by reference to the following description taken in connection with the accompanying drawings wherein like reference characters refer to like elements.

DRAWINGS

FIG. 1 is a schematic diagram of a first circuit according to the present invention;

FIG. 2 is a chart of waveforms illustrating operation of the FIG. 1 circuit;

FIG. 3 is a schematic diagram of a second circuit according to the present invention;

FIG. 4 is a schematic diagram of a third embodiment of the present invention; and

FIG. 5 is a schematic diagram of yet another embodiment according to the present invention.

DETAILED DESCRIPTION

Referring to FIG. 1, a multistable circuit according to the present invention comprises a plurality of latching circuits preferably comprising pairs of transistors. A first such pair comprises a first transistor Q_1 and a second transistor Q_5 . A second pair comprises transistors Q_2 and Q_6 , a third Q_3 and Q_7 , and a fourth Q_4 and Q_8 . The transistors of each pair are intercoupled in feedback fashion so that if one transistor conducts, both will tend to conduct heavily. Thus, the collector of Q_1 is coupled to the base of Q_5 by means of resistor 10, while the collector of Q_5 is similarly connected to the base of Q_1 employing resistor 12. Resistor 14 returns the base of Q_5 to a positive voltage, while resistor 16 returns the base of Q_1 to a negative voltage. Coupling means, comprising resistor 18, couples the collector of Q_1 to the base of Q_6 . A current source, i_2 , provides current at the emitters of Q_5 and Q_7 , while a current source

20 i_3 provides current at the emitters of Q_6 and Q_8 . In the embodiment of FIG. 1, the first transistors of each pair, i.e., transistors Q_1 , Q_2 , Q_3 , and Q_4 , are suitably NPN type, while the second transistor of each pair, i.e., transistors Q_5 , Q_6 , Q_7 , and Q_8 , are of complementary or 25 PNP type.

A current switching circuit comprising transistors Q_9 and Q_{10} is employed for providing current alternatively at the emitters of Q_1 and Q_3 or at the emitters of Q_2 and Q_4 . The emitters of Q_9 and Q_{10} are connected to a current source i_1 , while the collectors of Q_9 and Q_{10} are connected to the emitters of Q_1 and Q_3 and the emitters of Q_2 and Q_4 , respectively. The base of Q_{10} is returned to a negative voltage through resistor 20, and to ground via Zener diode 22. The base of Q_9 is also returned to a negative voltage employing resistor 24, while a Zener diode 26 couples the base of Q_9 to an input terminal 28.

Successive latching circuits are intercoupled in the same way as described above in connection with latching circuits Q_1 , Q_5 , and Q_2 , Q_6 , and are arranged in consecutive manner, with alternate transistor pairs receiving current via Q_9 or via Q_{10} . Pairs receiving current from Q_9 also receive current from source i_2 , while pairs receiving current from Q_{10} also receive current from source i_3 . Resistor 30 from the collector of Q_4 is connected at point Y to the base of Q_5 to provide a continuous circuit connection.

In considering operation of the circuit, let us assume that transistors Q_4 and Q_8 are conducting. Since the collector of each is connected to the base of the other, a feedback circuit is established, each holding the other in conduction. At this time, Q_{10} is on, providing current through transistor Q_4 and resistors 32 and 34 to a positive voltage source. The drop in resistor 34 insures the conduction of Q_8 whereby current i_3 flows through transistor Q_8 and resistors 36 and 38. Since the base of Q_4 is connected to the junction between resistors 36 and 38, continued conduction of Q_4 is assured.

At the same time, Q_4 , being coupled to the base of Q_5 via resistor 30, provides a part of the current i_1 from Q_{10} 60 through resistor 14 providing a drop in resistor 14 effective for turning Q_5 on. At this time, Q_1 will not be on inasmuch as no current is provided therefor. However, since Q_5 conducts, the latching circuit comprising Q_1 and Q_5 is preset so that when the current i_1 is switched, the pair Q_1 , Q_5 will immediately go into feedback conduction. Q_5 draws current through resistors 12 and 16 providing a voltage at the base of Q_1 presetting Q_1 for

conduction. Thus, when a positive pulse is applied at terminal 28, the base of Q_9 , previously in effect tied to a negative voltage, will be raised via Zener diode 26, causing Q_9 to conduct. Since the transistors Q_9 and Q_{10} are connected differentially, Q_9 will draw the current previously coupled through Q_{10} , and Q_{10} will cease conduction. Q_9 will now deliver current i_1 to the emitter of Q_1 , and transistor Q_1 will conduct immediately since it was preset for conduction. Q_1 now presets Q_6 via resistor 18.

Thus, when pair Q_4 , Q_8 conducts, transistor Q_5 of the next pair conducts and transistor Q_1 is preset for conduction. Q_1 conducts whenever and just as soon as current is provided via transistor Q_9 . Then when the signal input again goes negative, transistor Q_9 will be shut off, since the negative-going signal will drive the base thereof below cutoff, and Q_{10} will conduct. Since transistor Q_6 is conducting, transistor Q_2 will be turned on at its base, and current i_1 will immediately flow through transistor Q_2 . As a result, feedback conduction between transistors Q_2 and Q_6 is established. In this circuit, no commutation time is necessary between stages when an input signal transition takes place. Rather, at least one element of the next succeeding pair is always preset to a conducting condition or a condition ready for conduction at the same time as the previous pair is in a state of feedback conduction.

As an input waveform, for example a sine waveform 40 in FIG. 2, is applied to input terminal 28, transistors Q_9 and Q_{10} alternately conduct. The signal at the collectors of Q_9 and Q_{10} is substantially a square wave with positive alternations being designated T_1 and T_3 while negative alternations are designated T_2 and T_4 . At the time T_1 , or when Q_9 first conducts, transistor Q_1 will conduct and provide a negative-output, as illustrated. At time T_2 , transistor Q_2 conducts providing a negative-going output designated Q_2 in FIG. 2, etc. As hereinbefore mentioned, Q_5 is on at the same time Q_1 is on, but so is Q_6 . Q_6 continues to conduct at the time T_2 when Q_2 is on. Transistors Q_1 , Q_2 , Q_3 , and Q_4 conduct in that order and then, since Q_4 is connected to Q_5 , the cycle repeats. Transistors Q_5 through Q_8 turn on and off at every other transition of the input waveform thus representing a binary countdown by a factor of two in terms of the input frequency. The circuit is useful for any dividing function, ring counter function, or the like. Outputs are suitably derived from the collectors of transistors Q_1 through Q_4 by means of isolating transistors (not shown in this embodiment) or alternatively from the collectors of Q_5 through Q_8 by means of isolating transistors.

In the circuit of FIG. 1, only the latching circuit including a preset transistor will come on next when the current is switched between transistors Q_9 and Q_{10} . The non-preset transistor connected to the collector of Q_9 or Q_{10} is biased off. As a latching circuit goes into feedback conduction, a transistor of the next following pair is preset for maintaining the proper sequence in each case.

The circuit is not sensitive to the frequency of input presented at terminal 28. The waveform may be very slowly changing and the circuit will operate as described. However, the circuit will continue to operate at high frequencies. For example in integrated circuit operation, the circuit has operated up to a frequency of 600 megahertz.

In FIG. 3, another embodiment of the present invention is illustrated, wherein the latching circuits are formed slightly differently. This time, the first latching circuit comprises a first transistor Q_1 and a second transistor Q_6 . The remaining latching circuits comprise transistors Q_2 and Q_7 , Q_3 and Q_8 , and Q_4 and Q_5 , respectively. Thus, when the transistor Q_4 conducts, current is drawn through resistors 42 and 44 in series from a positive source, wherein the voltage at the junction between the resistors causes transistor Q_5 to conduct. Similarly, transistor Q_5 draws current from a positive source through resistors 46 and 48, raising the voltage at the base of Q_4 and holding the latter transistor in a conducting state. At this time, it is assumed a current i_1 is provided through transistor Q_{10} to transistor Q_4 in the same manner as hereinbefore described in connection with the embodiment of FIG. 1.

The collector of Q_5 is coupled to the base of Q_1 with resistor 50 at point Z, so also at this time current is coupled from the collector of Q_5 through resistor 50 and resistor 52 to ground. The voltage drop across resistor 52 raises the base voltage of transistor Q_1 presetting transistor Q_1 for conduction. As soon as a positive-going signal is received at terminal 28, current is delivered through transistor Q_9 to the emitter of Q_1 and the latter immediately conducts inasmuch as it is preset for conduction. As Q_1 conducts, current is drawn through resistors 54 and 56 thereby lowering the voltage at the base of Q_6 , whereby Q_6 conducts. As Q_6 conducts, current flows through resistors 58 and 52 for maintaining the voltage across resistor 52 at a value for retaining Q_1 in a conducting state. As the current i_1 transfers from Q_{10} to Q_9 , the source of current for resistor 52 shifts from Q_5 to Q_6 , but is sufficient for maintaining Q_1 in conduction.

A further modification of the invention is illustrated in FIG. 4. This circuit is similar to the FIG. 3 circuit, and like elements are designated similarly. The resistor between the collector of a first transistor of a given latching circuit and the base of a second transistor of the same latching circuit has been eliminated. For example, the collector of first transistor Q_1 is directly connected to the base of second transistor Q_6 without an intervening resistor, since such resistor is not necessary to circuit operation, and the schematic diagram is thereby simplified. With switch 60 in the position shown, circuit operation will be identical to that of the circuit of FIG. 3. That is, the feedback conduction in each latching pair presets a transistor of the next pair such that when the current shifts in response to an input signal, the next latching pair will conduct. Thus, as current shifts from Q_{10} to Q_9 , transistors Q_4 and Q_5 cease conduction while transistors Q_1 and Q_6 start conduction. However, the FIG. 4 circuit is provided with additional transistors Q_5' , Q_6' , Q_7' , and Q_8' . Each of the last mentioned transistors comprises an additional second transistor for each latching pair. When switch 60 is in the position shown, these additional transistors are not energized. However, when the switch is thrown from position F to position B, transistors Q_5' , Q_6' , Q_7' , and Q_8' are energized in place of the non-primed second transistors. In the latter event, the latching pairs comprise transistors Q_1 and Q_5' , transistors Q_2 and Q_6' , transistors Q_3 and Q_7' , and transistors Q_4 and Q_8' .

Let us assume that transistors Q_4 and Q_8' are conducting with switch 60 thrown into position B. Current

from the collector of Q_4 flows through resistor 62 maintaining the conduction of transistor Q_8 while the collector current from transistor Q_8 flows through resistors 64 and 66 for maintaining transistor Q_4 in a conducting state. The collector of transistor Q_8 is also coupled to the base of transistor Q_3 via resistor 68 and a current flows through resistor 68 and resistor 70 located between the base of transistor Q_3 and ground. Transistor Q_3 is thus preset for conduction. Now, when a positive-going signal is received at terminal 28, and current i_1 switches from transistor Q_{10} to transistor Q_9 , transistor Q_3 will conduct instead of transistor Q_1 inasmuch as transistor Q_3 was preset through resistor 68. With succeeding transitions at input terminal 28, the multistable circuit will operate in a reverse direction such that each latching pair in succession from right to left becomes conductive and presets the next. Switch 60 is thrown to R for reverse operation, and to F for forward operation.

A further embodiment of the present invention is illustrated in FIG. 5 and employs entirely NPN transistors. The circuit is therefore easily implemented in an integrated circuit construction. It will be appreciated by those skilled in the art that the various diodes illustrated in the circuit are easily fabricated in the same integrated circuit construction with the NPN transistors. The transistor pairs comprising latching circuits respectively comprise transistors Q_1 and Q_6 , transistors Q_2 and Q_7 , transistors Q_3 and Q_8 , and transistors Q_4 and Q_5 .

In the FIG. 5 circuit, the emitters of transistors Q_1 and Q_3 receive current from the collector of Q_9 , while the emitters of transistors Q_2 and Q_4 are similarly connected to receive current from the collector of Q_{10} . The collector of Q_1 is directly connected to the base of Q_6 , while the emitter of Q_6 is returned to ground through a resistor 72. Transistor Q_6 is one of the differential pair of transistors and the emitter of transistor Q_6 is connected to the emitter of transistor Q_{11} , the latter having its base connected to a source of reference voltage, R. The collector of transistor Q_{11} is returned to a positive voltage, and the collector of transistor Q_6 is coupled to the same positive voltage through resistor 74. Transistors Q_6 and Q_{11} comprise a current switching pair or differential amplifier circuit for switching the current passing through resistor 72 so that it flows either to Q_6 or Q_{11} .

The collector of transistor Q_6 is also connected to the cathode of a Zener diode 76, the anode of which is connected to the base of transistor Q_1 . The anode of diode 76 is returned to ground via resistor 78. Also, the collector of transistor Q_6 is coupled to the base of transistor Q_2 of the next latching circuit by way of Zener diode 80 having its anode connected to the base of Q_2 as well as through resistor 82 to ground.

The collector of transistor Q_1 is coupled through resistor 84 to the emitter of an isolation transistor 86 having its base connected to the junction between a diode 88 and a resistor 90 interposed in that order between a positive voltage and ground. A resistor 92 connects the collector of transistor 86 to a positive voltage, and an output terminal 94 is also connected to the collector of transistor 86. Transistor 86 operates as a common base transistor amplifier for isolating the Q_1 , Q_6 latching pair from an output load which may be connected at terminal 94.

Each of the stages is substantially identical, and the last latching pair, Q_4 , Q_5 , is connected to the first latching pair at point X. The collector of transistor Q_5 is connected to a positive voltage through resistor 96 and the emitter of transistor Q_5 is returned to ground via resistor 98. The emitter of transistor Q_{14} is also connected to the emitter of transistor Q_5 while the collector of Q_{14} is connected to a positive voltage. A resistor 100 is located between the collector of transistor Q_4 and the emitter of an isolating transistor 102. Zener diode 104 is disposed between the collector of transistor Q_5 and the base of transistor Q_4 . Also a Zener diode 106 is connected between point X and the base of Q_1 , the anode of the Zener diode being connected to the base of Q_1 .

Let us assume transistor 10 is on and that the feedback pair comprising transistors Q_4 and Q_5 is operated. Transistor Q_4 is conducting and transistor Q_5 is nonconducting. The current from the collector of Q_{10} passes through Q_4 and resistor 100 dropping the voltage at the base of transistor Q_5 . Transistor Q_{14} conducts instead of Q_5 , and voltage at the collector of Q_5 is high. The voltage level at the collector of transistor Q_5 is reduced by Zener diode 104 so that it is appropriate for application at the base of transistor Q_4 for maintaining the conduction of Q_4 . Transistors Q_4 and Q_5 are thus connected in a feedback arrangement. Also, the voltage at the collector of transistor Q_5 is applied at point X to Zener diode 106, located between the collector of Q_5 and the base of Q_1 . Therefore, the voltage at the base of Q_1 presets Q_1 for conduction. Now, when a positive-going voltage is received at terminal 28 and current i_1 shifts, transistor Q_1 will conduct inasmuch as the latter is the only transistor among transistors Q_1 , Q_2 , Q_3 , and Q_4 which has been preset for conduction. The change in the condition of Q_1 , of course, is coupled to terminal 94 via transistor 86.

The circuits according to the present invention are not encumbered by rate or rise time determining commutation components, but rather the next stage to be on is preset at the same time the previous stage goes into conduction, and therefore commutation problems are substantially nonexistent. As hereinbefore mentioned, the circuit will operate and keep step with an input changing at an exceedingly low or substantially d.c. switching rate, up to a signal of several hundred megahertz. The various multistable circuit stages themselves provide suitably divided outputs, or may be combined in various manners to produce a desired output pulse configuration. Although each of the circuits illustrated includes four latching stages, it will be appreciated that stages may be added as desired. E.G., two of the circuits of the present invention may be employed together, with the output of each circuit operating as the input of the other circuit.

While I have shown and described several embodiments of my invention, it will be apparent to those skilled in the art that many changes and modifications may be made without departing from my invention in its broader aspects.

I claim:

1. A multistable circuit comprising: a plurality of latching circuits each comprising a pair of transistors interconnected in a feedback arrangement, and means for directly and continuously coupling a first feedback pair to a control electrode of a transistor of a second feedback pair so that the

- transistor of the second feedback pair is preset for conduction at the time that feedback conduction takes place in the first pair.
2. The circuit according to claim 1 wherein said transistor of said second pair is provided current so that it conducts substantial operating current at the same time the first pair conducts.
3. The circuit according to claim 1 further including current switching means for switching supply current between transistors of said first and second pairs.
4. A multistable circuit comprising:
- a plurality of feedback circuits each comprising a first transistor and a second transistor and coupling means between said transistors so that conduction in one transistor tends to predetermine the state of the other transistor,
- means for coupling a collector of one transistor of each prior pair to the base of a transistor of a next pair in sequence for presetting that transistor of the next pair for conduction, at the time that feedback conduction takes place in the prior pair,
- and current switching means for switching a predetermined supply current between alternate feedback pairs respectively coupled by said coupling means so that when current is switched, the transistor pair including the preset transistor goes into feedback conduction.
5. The circuit according to claim 4 wherein a first transistor of each pair is connected to said current switching means and wherein said coupling means couples the collector of a second transistor of each pair to the base of the first transistor of the next pair for resetting the same.
6. The circuit according to claim 4 wherein the first transistor of each pair is connected to said current switching means and wherein the collector of the first transistor of each pair is coupled by said coupling means to the second transistor in the next pair for turning on such second transistor of the next pair and presetting the first transistor of the next pair.
7. The circuit according to claim 4 further including additional second transistors wherein each additional second transistor is also coupled with one of said first transistors to form a feedback pair and additional coupling means for coupling each additional second transistor to a first transistor of a prior pair,
- and means for selectively providing current to said second transistors or to said additional second transistors for securing reversible presetting in said multistable circuit.
8. The circuit according to claim 4 wherein said first and second transistors are of opposite conductivity types, and wherein both transistors of a given pair are adapted to conduct at the same time during feedback operation.
9. The circuit according to claim 4 wherein the coupling means from a last transistor pair in sequence is coupled for presetting a transistor of a first transistor pair in the same sequence.
10. The circuit according to claim 4 wherein said first and second transistors are of complementary conductivity types, and further including a second source of current for said second transistors.
11. The circuit according to claim 4 wherein said first and second transistors are of the same conductivity type and further including Zener diode voltage dropping means for coupling the output of each second transistor to the input of the first transistor of the same pair.
12. The circuit according to claim 11 wherein said coupling means between a feedback pair and a transistor of the next pair for presetting the same comprises a Zener diode.
13. The circuit according to claim 4 wherein said first and second transistors are of the same conductivity type and further including an additional transistor associated with each pair connected in a differential amplifier circuit with the second transistor of each pair.
14. A multistable circuit comprising:
- a plurality of latching circuits each including a feedback pair of active elements, wherein said first ones of said latching circuits are adapted to alternate in operating sequence of feedback conduction with second ones of said latching circuits,
- means for applying a voltage from a given latching circuit to one of the active elements of the next latching circuit for presetting such element at the time when feedback conduction takes place in the given latching circuit,
- and means for providing a current to the said one element of the next latching circuit so that substantial current conduction takes place therein as the same is preset at the same time that feedback conduction takes place in the given latching circuit, thereby enabling subsequent feedback conduction in the next latching circuit.
15. A multistable circuit comprising:
- a plurality of latching circuits, each including a feedback pair of active elements, wherein first ones of said latching circuits are adapted to alternate in operating sequence of feedback conduction with second ones of said latching circuits,
- means for applying voltage from a given latching circuit to one of the active elements of the next latching circuit causing such element to be preset for conduction at the time when feedback conduction takes place in the given latching circuit,
- means for applying a voltage from the said given feedback circuit to an active element of a prior latching circuit in sequence,
- and means for selecting between forward and reverse operation of such multistable circuit.
16. A multistable circuit comprising:
- a plurality of latching circuits each comprising a pair of transistors interconnected in a feedback arrangement, said transistors having collector electrodes and control electrodes,
- and means for directly and continuously coupling a collector electrode of a transistor of a first feedback pair to a control electrode of a transistor of a second feedback pair so that the transistor of the second feedback pair is preset for conduction at the time that feedback conduction takes place in the first feedback pair.
17. The circuit according to claim 16 wherein said direct coupling means comprises a resistor.
